(57) **CLAIM**

The ornamental design for an electrosurgical generator, as shown and described.

DESCRIPTION

FIG. 1 is a top front perspective view of an electrosurgical generator, showing our new design;

FIG. 2 is a top rear perspective view of the electrosurgical generator of FIG. 1;

FIG. 3 is a top plan view of the electrosurgical generator of FIG. 1;

FIG. 4 is a bottom plan view of the electrosurgical generator of FIG. 1;

FIG. 5 is a right side elevational view of the electrosurgical generator of FIG. 1;

FIG. 6 is a left side elevational view of the electrosurgical generator of FIG. 1;

FIG. 7 is a front elevational view of the electrosurgical generator of FIG. 1; and,

FIG. 8 is a rear elevational view of the electrosurgical generator of FIG. 1.

The broken lines shown in the figure drawings are included for illustrating environmental structure and form no part of the claimed design.
